UNITED STATES PATENT OFFICE.

ORLANDO SHEPPARD, JR., OF ATLANTA, GEORGIA, AND RUSSELL A. TRACE, OF DAYTON, OHIO, ASSIGNORS TO BUCKEYE IRON & BRASS WORKS, OF DAYTON, OHIO, A CORPORATION OF OHIO.

PROCESS AND APPARATUS FOR CHARGING COOKERS.

Application filed March 28, 1921. Serial No. 456,454.

To all whom it may concern:

Be it known that we, ORLANDO SHEPPARD, Jr., and RUSSELL A. TRACE, citizens of the United States, residing, respectively, at 5 Atlanta, in the county of Fulton and State of Georgia, and at Dayton, in the county of Montgomery and State of Ohio, have invented certain new and useful Improvements in Processes and Apparatus for Charging 10 Cookers, of which the following is a specification, reference being had therein to the accompanying drawing.

Our invention relates to a method and apparatus utilized in the cooking of cotton 15 seed meal and in particular to apparatus for effecting the proper handling and passage of oil bearing material through the cooker to the former and presses.

The object of our invention is to provide 20 some means of informing the press crew of the time when they should start emptying the presses of oil bearing cake or cake that has contained oil which has been expressed therewith and the time for reloading the 25 presses by charging the former from the lowermost kettle and taking the cakes from the former to the presses.

It will be understood that in oil mills 30 there is a layout of machinery, as will be seen in Figure 4, consisting of machinery for supplying proper oil bearing material to the cooker, a cooker, a former, and a plurality of presses. The whole mechanism is worked on a schedule depending upon the 35 amount of time it takes for a charge of meal to be properly cooked so that it can be delivered to the former. This schedule is usually arranged in cycles of twenty minutes each. It has been very difficult heretofore 40 to secure a uniform adherence to the schedule where dependence was placed upon a clock or upon the adjustment of the mechanism itself. The exact time is not essential save that the machinery runs in cycles of approxi- 45 mately a predetermined period, but the difficulty has been in keeping the timing in operating the machinery in accordance with the time schedule followed on a clock because the machinery would get out of time 50 with the clock and thus upset the schedule.

By our invention we are enabled to work 55 the machinery on the proper cycles and give notice of the time of operating it when the machinery has actually performed its cycle of functions so that if the machine takes a

few seconds more at some time than at others it will not upset a pre-arranged schedule.

Referring to the drawings:

Fig. 1, is a side elevation of a plurality of kettles of a cooker with operative mechanism for opening and closing the several gates for charging and discharging the oil bearing materials from the kettles, together with the alarm mechanism; 60

Fig. 2, is a section of the alarm; 65

Fig. 3, is a detail view of the alarm and the operating mechanism therefor; and,

Fig. 4, is a plan view of the machinery as laid out in an oil mill where my method is practiced. 70

Describing the particular parts in these drawings, 1, 2, and 3 are kettles superimposed above one another, the lowermost kettle communicating with a former 4. These kettles are provided with doors 5 pivoted at 6 on a shaft 7 and carried thereby. These doors engage with a trap 8 to seal the bottom of the cooker to prevent the exit of meal. The arm 9 is connected with a cross shaft 7. The arm 9 has a weight 10 upon the end thereof to maintain the gate 5 in its closed position. A trip arm 11 is pivoted to the cooker at 12, the function of which will be explained hereinafter. 75

The cooker is operated through a flexible 80 chain or some desired flexible member or a driving member 13 which is actuated by a drive wheel 14 and a sprocket 15 carried on the shaft 16 journaled in the support 17. This flexible member is guided by a guard 85 18 to some extent, the guard also performing the function of preventing injury to the operator. A lug 19 is carried by the chain 13 which comes in contact with the cam surfaces 20 affixed to the shaft 7. This lug 19 also comes in contact with the arm 21 on 90 which is mounted a weight 22 that actuates the gear segment 23 to ring the alarm bell 24. 95

The alarm bell itself, as will be seen in Figure 2, consists of the bell 24 that has 100 a lug cast on the interior thereof at 25. It is retained on the cooker by a bolt 26. Upon this bolt 26 is mounted loosely a gear member 27 that meshes with the gear segment 23 that is supported on the lever 21 pivoted at 28 to the cooker 1. Thus 27 and 23 mesh with one another so that 23 will rotate 27 on 26. 27 is projected outwardly and laterally to form an internal gear 29 which meshes with a pinion 30 carried on a plate 110

31 which travels inside of the bell 24. This plate 31 has mounted loosely upon it the centrifugally operated members 32. These members are retained on the plate by the 5 studs 33 and cap plates 34.

When 23 rotates 27 it consequently rotates 32 thus imparting motion through 30 to the plate 31 so that centrifugal force of the rotation of 31 will throw outwardly the 10 centrifugally operated members 32 which will strike against the lug 25 on the interior of the bell and thus ring the bell.

The actuation of 23 is secured as follows: As the lug 19 passes around on the 15 chain 13 it comes in contact with the end 21 of the arm that carries the weight 22 thus lifting it slowly as the chain usually makes a complete cycle in about twenty minutes. When the lug 19 passes by the 20 arm 21 it is allowed to drop suddenly by reason of the weight 22 pulling it downwardly. This actuates the gear 23 around the pivotal point 28.

The lug 19 travels upwardly, the bottom 25 cooker being emptied this time, and comes in contact with the cam member 20 thus elevating the arm 9, the weight 10, and opening the door 5 allowing the meal from the kettle 2 to drop into kettle 1 to fill it. 30 This movement throws the arm 9 and the weight 10 into the dotted line position against the trip arm 11 so that the door remains in open position. As the trip moves upwardly it comes in contact with the upper 35 end of 11 and moves it to the right hand about the pivot 12 thus throwing the weight 10 and arm 9 back into their original closed position, closing the gate 5, the arm 9 coming into contact with the spring buffer 35.

40 Referring to Figure 4, meal is supplied to the trough 36 thence through the trough 37 to the trough 38 into the overhead feed trough 39 whence it goes into the topmost cooker 40 and descends as described to the 45 lowermost kettle 1 where it is drawn out into the former 4 by the press crew and thence delivered by the press crew to the presses 41 in the form of cakes.

The press crew start to unload the presses 50 41 when the bell rings during which time the lowermost kettle is being filled from kettle No. 2. By the time they have taken out a portion of the cakes the former is ready to be started and filled from the lowermost kettle of the cooker, which has now 55 been filled. They, therefore, form the cakes and fill the presses while the meal is being shifted in the kettles above No. 1. They then wait until the alarm rings the second 60 time when they start the operation over again.

While we have shown and described certain features as constituting our invention, it will be understood that parts have been 65 shown for purposes of illustration only, and

that we do not desire to be limited to such details, as obvious modifications will occur to a person skilled in the art.

Having thus fully described our invention, what we claim as new and desire to secure 70 by Letters Patent, is:—

1. In a cooker, means for cooking oil bearing material, means for loading and unloading said cooker, an alarm and means actuated by said loading and unloading means 75 for operating said alarm at predetermined intervals of time of its operation to indicate the unloading of the cooker.

2. In a cooker, a plurality of kettles, a plurality of means for opening and closing 80 the kettles for the discharge of oil bearing material from one kettle to another, mechanism for actuating said discharging means successively, and an alarm for indicating the state of the apparatus, and means carried by 85 said actuating means for operating said alarm upon completion of each cycle of operation of said actuating mechanism.

3. In combination, a plurality of kettles superimposed above one another, gates for 90 said kettles attached to each of said kettles to permit of the discharge of oil bearing material from one kettle to another, means normally urging said gates to closed position, a traveling member to open said gates at predetermined intervals, and an alarm positioned to be actuated by said traveling member upon completion of each cycle of operation of said traveling member.

4. In combination, a plurality of kettles superimposed above one another, gates for 100 said kettles attached to each of said kettles to permit of the discharge of oil bearing material from one kettle to another, means to keep said gates normally closed, means to successively open said gates at predetermined intervals of time, and a pivoted trip arm actuated by said opening means to move said gates to closed position after a predetermined interval of time.

5. In combination, a plurality of kettles superimposed above one another, an endless chain traveling adjacent thereto, means of driving said chain, an actuating lug carried by said chain and traveling therewith, an arm pivoted to the lowermost kettle having a weight thereon at one end and a gear segment at the other end, a bell adapted to be actuated by said gear segment, said arm adapted to be actuated by said lug on the chain. 115

6. In combination, a plurality of kettles superimposed above one another, an endless chain traveling adjacent thereto, means of driving said chain, an actuating lug carried by said chain and traveling therewith, an arm pivoted to the lowermost kettle having a weight thereon at one end and a gear segment at the other end, a bell adapted to be actuated by said gear segment, said arm adapted to be actuated by said lug on the 120 125 130 chain.

chain, gates in said kettles normally closed, means for maintaining said gates in their closed position, means thereon to be actuated by said lug by the chain for opening said gates, and means to be actuated by said lugs for closing said gates.

7. In a method of operating a cotton seed oil mill, preparing the oil bearing material, conveying the oil bearing material to a cooker, transferring the oil bearing material by operation of mechanism connected with the cooker to successive kettles in said cooker, and sounding through the operation of the mechanism an alarm at the end of a certain definite period to notify the press crew to operate a former and the presses.

8. In a method of operating a cotton seed

oil mill, preparing the oil bearing material, conveying the oil bearing material to a cooker, transferring the oil bearing material by continuous operation of mechanism connected with the cooker to successive kettles in said cooker, sounding through the operation of said mechanism an alarm at the end of a certain definite period to notify the press crew to operate a former and the presses, operating a former and operating the presses by withdrawing cakes that have been pressed and inserting unpressed cakes from the former.

In testimony whereof, we affix our signatures.

ORLANDO SHEPPARD, JR.
RUSSELL A. TRACE.
